(No Model.)

S. W. HUDSON.

AIR BLAST.

No. 250,073.

Patented Nov. 29, 1881.

UNITED STATES PATENT OFFICE.

SAMUEL W. HUDSON, OF HUDSONDALE, PENNSYLVANIA.

AIR-BLAST.

SPECIFICATION forming part of Letters Patent No. 250,073, dated November 29, 1881.

Application filed September 5, 1881. (No model.)

To all whom it may concern:

Be it known that I, SAMUEL W. HUDSON, of Hudsondale, in the county of Carbon and State of Pennsylvania, have invented certain new and useful Improvements in Air-Blasts, of which the following is a specification.

The object of my invention is to provide an apparatus by which, with a given primary or initial blast, a blast of increased volume but decreased pressure or velocity may be produced as desired.

In the accompanying drawings, Figure 1 is a vertical longitudinal section, and Fig. 2 a transverse section on the line 2 2 of Fig. 1.

15 A is an ordinary blower-fan, its blast being delivered through the pipe a. The pipe a extends into the flaring end of a pipe, B, of larger diameter, and the pipe B in the same manner projects into a larger pipe, C. Sliding collars 20 or cut-offs D D on the pipes a and B serve to close or regulate the size of the annular openings x and y between the pipes a and B and the pipes B and C, as will be clear from the drawings. The fan A, being driven at a given 25 speed, will produce a blast through a, which will draw air through the annular opening x, thus increasing the volume and decreasing the velocity. The blast, passing on through B, in like manner draws in air through the annular 30 opening y. The collars can be adjusted to vary the size of the openings and regulate the volume of the blast delivered at Z. Thus, for ex-

ample, with a blast in a, with a volume of one hundred feet and a pressure of six pounds per square inch, I may produce at Z a blast having 35 a volume of six hundred feet and a pressure of one pound.

It will be seen that the fan may be run at a uniform speed and the character of the blast varied by adjusting the collars on the pipe. 40 The primary blast may be generated in any suitable manner.

My invention may be used in connection with exhaust or pressure ventilating apparatus, or for any other purpose where such an opera- 45 tion as that above described is desirable.

What I claim is—

1. The combination of the blower-fan, the blast-pipe a, and the pipes B and C, projecting one within the other and having flaring ends, 50 substantially as described.

2. The combination of the blower-fan, the pipes a, B, and C, and the sliding regulating-collars D, substantially as set forth.

3. The combination of the blast-pipe, the 55 air-supply pipe into which the blast-pipe projects, and a device for controlling and regulating the air-supply, as set forth.

In testimony whereof I have hereunto subscribed my name.

SAMUEL W. HUDSON.
